7 Claims. (Cl. 57—34)

This invention relates in general to the texturizing of thermoplastic yarns and more particularly to an improved system permitting a plurality of yarn passes through a single heater prior to passage into a false twisting device.

In the production of texturized yarn by the system to which this invention pertains, thermoplastic yarn usually is fed from a supply source into a heater and then through a false twister to a suitable withdrawal and/or collection means. Twist imparted by the false twister backs up through the yarn contained within the heater, and the heater functions to set this twist. Upon removal of twist by passage of the yarn to the opposite side of the twist point there is an inherent tendency caused by heat setting for that twist to return, which produces a bulky or voluminous effect. If the yarn is permitted to cool between the heat setting zone and the twist imparting zone, the tendency to shrink and bulk becomes permanent, all as is well known to this art.

It is obvious that this novelty type yarn may be produced more economically if higher twisting and heat setting speeds can be obtained without deleteriously affecting the end product. Various technical difficulties are encountered, however, when higher processing speeds are attempted. The yarn must be twisted a certain minimum number of turns per inch, and the twisted yarn must be maintained at a certain temperature for a minimum period of time to insure proper heat setting. Moreover, the heat setting temperature is limited by the melting point of the yarn processed, which usually results in an increased time for passage through the heater, rather than increased temperature. An increase in velocity or speed of the running yarn also affects the heat setting stage, and usually must be accompanied with an increased length of yarn exposed to elevated temperature, which heretofore meant that the heater length must be extended if higher speeds were desired.

As a result of the aforesaid speed increases and melting point limitations, heaters have now acquired undesirably large dimensions, which not only raises the cost thereof, but also hampers threading up and other operations. Moreover, the heater length contributes substantially to the overall height of the machine frame with which the same is associated.

In the past it was felt that heater length could be shortened by guiding yarn one or more passes through the same by the use of reversing rollers or the like. Although these rollers indeed appear to guide the yarn without appreciable tension increase, it has been found that they hinder passage thereover of the false twist. In other words, reversing means used heretofore prevented twist from backing up past that point, or locked the twist to the last length of yarn running through the twist setting means. An example of the type reversing means experimented with in the past may be found in U.S. Patent No. 923,425, particularly FIGURE 5, which issued on June 1, 1909, to Gin et al.

A primary object of the present invention is to provide a texturizing process and apparatus not having disadvantages such as discussed above.

An additional object of this invention is to provide a novel texturizing process and apparatus permitting high

2

speed operation with conventional length twist setting equipment.

Another object of the present invention is to provide a system for threading up a texturizing device enabling a plurality of yarn passes through a twist setting unit while permitting twist back up throughout the length of yarn contained in the unit.

Still another object of this invention is to provide a yarn direction reversing means or guiding system not accompanied by twist lock for use in combination with a false twister-heat setting type texturizing apparatus in order to permit reduction in heater length even at higher false twister speeds.

A conventional yarn texturizing apparatus including a supply source, feed means, twist barrier, twisting device, twist setting unit and withdrawal means may be improved, in accordance with the present invention, by adding guides defining multiple passes of yarn through the twist setting unit, and by providing means for reducing friction or for causing slippage of yarn over these guides, whereby twist imparted by the twist device may travel through every portion of yarn contained in the setting unit back to the twist barrier. If a guide rod is used at the direction reversing points, the slippage may be caused by moving the guide in the direction as the twist or by vibrators, and if rollers are used for reversing the yarn direction, the slippage may be caused by driving the same at a speed in excess of the yarn speed. In either case, the resistance to yarn twisting is lowered sufficiently to permit passage of twist thereover. Consequently, the twisting device produces twist in each length of yarn passing through the setting unit, and this unit accordingly functions as before to set twist, but now in a plurality of lengths. Usually, setting is accomplished by subjecting the twisted yarn to elevated temperature, as explained earlier.

As a result of the presence of the guiding system described above, it is now possible to pass yarn several times along or through the same heating and/or cooling surface, and the yarn will be highly twisted over the whole path in which thermal yarn treatment may occur. Accordingly, in addition to the apparatus mentioned, this invention also relates to an improved method for heating or cooling twisted thermoplastic yarn by passing the same a plurality of times in twisted condition along a known setting surface.

Other objects and advantages will become apparent upon study of the following detailed disclosure taken in conjunction with the accompanying drawings, wherein

FIGURE 1 is a side elevational view of a complete yarn texturizing apparatus, modified in accordance with one embodiment of this invention;

FIGURE 2 is an enlarged view of the guide means shown in FIGURE 1;

FIGURE 3 is a detailed elevational view similar to FIGURE 2 but showing a second embodiment of the guide or direction reversing means; and

FIGURE 4 is an elevational view showing still another modification of the guide system and means for reducing the frictional drag thereof.

In FIGURE 1, one thermoplastic texturizing position is indicated generally by reference numeral 10. It should be understood that a complete machine will be equipped with a plurality of these units or positions. Yarn 11 is withdrawn from package 12 through pigtail guide 13 by feed means 14, which usually consist of two steel drive rollers and a rubber coated pressure roller. These rollers may be driven by any convenient means, not shown. From the rollers 14, the yarn is passed through a twist barrier or twist lock formed by pressure rollers 15 and fed into the heating unit 16. Heater 16 as illustrated is a narrow tube formed, preferably, from stainless steel

and provided at each end with suitable terminals through which an electrical current may be passed. The heater serves as a fixation zone wherein the false twist is set. It is obvious, of course, that other type heaters and other sources of heat could be employed.

A thread guiding system 17 is provided in alignment with and adjacent one end of the tubular heater 16. This guide functions to reverse the direction of yarn passing through the heater, and to permit an additional pass before complete discharge therefrom. The first length of yarn 11 leaving heater 16 circles guide 17 approximately one-half turn, as illustrated in the detailed views, and returns for additional heat treatment. It will be evident that more than two passes may be provided simply by adding guides 17 to each end of the heater.

From tubular heater 16, yarn 11 is passed through a cooling zone into the false twisting device indicated at 18. This device may be rotated by any suitable means, not shown, and also may be of any known construction, but should be of the high speed variety if this invention is to be utilized to full advantage. Yarn is withdrawn from the twister 18 by a ring twister take-up 20, although other take-ups, of course, could be utilized. Pigtail guide 21 also serves as a twist barrier or stop to prevent false twist imparted by device 18 from passing into the package 22.

False twist device 18 twists yarn extending forwardly therefrom up to guide 21 in a first direction, say S-twist, and twists yarn extending back to twist barrier 15 in the opposite direction, Z-twist in this instance. It can be seen, therefore, that the yarn contained within heater 16 is in a highly twisted condition, but that this twist will be removed upon passage of that portion to the package 22. The heater 16 serves to set or crimp the yarn while twisted so that there will be an inherent tendency for the packaged yarn to return to the twisted condition. All of this, of course, is known to those skilled in this art.

A simple construction enabling pack up of twist through both lengths of yarn contained within heater 16 will now be described. The guide system 17 in this instance comprises an elongated wire or rod 23, preferably formed from stainless steel. This wire should be shifted or driven in a direction transversely to that of yarn travel at a velocity corresponding with the circumferential velocity in a tangential direction of the false-twisted yarn. In other words, the circumferential velocity of the yarn being twisted should correspond or be equal to the velocity of lateral movement of the surface of rod 23. Consequently, frictional drag normally imparted to the yarn by the guide will be negligible and the guide will not restrain rotation of yarn about its axis upon encirclement as shown in FIGURE 2. The guide rod 23 of course should be endless, or of infinite length, if the same is to operate over long periods of time. In this connection, it is pointed out that a single rod 23 could be utilized over an entire machine and serve as a direction reversing means at each texturizing position. Since the rod speed is correlated to the twist continuously placed in the yarn, the yarn in effect rolls over the rod and consequently may be twisted not only in that portion supplied to the rod but also in the portion discharged therefrom. The rod 23 may be driven by any suitable means, not shown.

With attention now directed to FIGURE 3, the second embodiment will be described. The guiding system 17 of this figure consists essentially of a conventional type guide bar 24 which is vibrated at a high frequency by vibrators 25, 26. These vibrators are available on the market, and may be of the type discussed in German Patent No. 743,309, issued on December 22, 1943. The vibrator 25 produces high frequency oscillations radially in bar 24, and vibrator 26 produces similar type oscillations axially of the bar. It is possible, of course, to utilize either or both vibrators, as desired. As a result of the high frequency vibrations, not only is the frictional

resistance to yarn travel reduced, but also the resistance to rotation of yarn produced by the twisting operation is eliminated so that the twist may run back in the yarn past the guiding system. As a result, twist is imparted

5 to both lengths of yarn contained within the heater, and the setting operation produces at least twice the amount of work heretofore obtained from this length heater. The means 25, 26 vibrate bar 24 in two mutually perpendicular directions with a mutual difference in phase, as indicated by arrows. The phase difference between vibrators, the frequency and the amplitude are so adjusted 10 that the bar is forced into a circular vibrating condition, the rotative velocity of which corresponds to the velocity of the steel rod 23, discussed in connection with FIGURE 2.

When utilizing the embodiment of FIGURE 3, it will be apparent that the frequency of vibratory oscillation should be sufficiently high that inherent inertia of yarn 11 will prevent the same from following the rapid movement of guide rod 24. When this condition exists, in 15 vibrator 25, for example, the loop of yarn 11 will be maintained in an apparently flying condition about the rod. Theoretically, of course, yarn 11 contacts rod 24 about 20% of the time and is out of contact with this rod for the remaining time, due to the rapid lateral or transverse rod movement relative to the yarn. Consequently, there quite possibly is a storage of yarn twist 20 during the contact period and a release of twist during the non-contact period. Due to the extremely high frequency of vibration, however, the practical effect is to 25 substantially remove any obstruction which might prevent passage of twist over this particular yarn reversing guide. Accordingly, it will be seen that the extent of 30 yarn contact with vibrating rod 24 obviously depends upon the frequency of oscillation as well as the viscosity of the air layer immediately surrounding and lying between these elements. Highly viscous air surrounding 35 yarn 11, of course, would restrain rapid yarn movement and promote separation between the rod and yarn during operation of the vibrator 25, whereas a vacuum condition would not prevent yarn movement in response to rod vibration and thereby would not facilitate floating. Imparting of a high speed oscillation to vibrator 25 of course permits elimination of initial sliding or starting 40 friction to facilitate passage of twist over rod 24. Slippage produced by axially vibrating rod 24, therefore will be somewhat similar to that described in connection 45 with the FIGURE 2 embodiment.

Another advantage to the aforesaid device is that the 50 tension in both passes or sections of yarn is substantially the same as the total "false-twist" tension. Moreover, the number of rotating or moving parts is considerably less than in the first embodiment described. For best 55 results, the slippage producing means 25, 26 should vibrate the yarn in a direction transverse to the passage of yarn about the bar 24. A more important advantage, however, is that the yarn may be vibrated in two directions at once, the plane of which is parallel to the running-on and running-off surfaces on the bar, and the sense of 60 rotation of which is opposite to the direction of yarn travel.

The third embodiment is illustrated in FIGURE 4. The guiding system 17 is here represented by a guide roller 27 about which the yarn is passed. This roller is so driven 65 in the direction of yarn travel, as indicated by the arrow, that the relative velocity between the periphery thereof and yarn in contact therewith is considerably greater than the velocity of the yarn fed through the heater. Any suitable means, not shown, may be used for rotating roller 70 shaft 28 and the roller 27 fixed thereto. The relative movement between yarn and guide roller reduces the frictional drag and resistance to twist, much in the manner described above, and therefore permits passage of twist 75 imparted by device 18 through the guiding system, and back to twist barrier 15.

Various other guiding systems may be designed for reversing yarn direction without stopping the twist. For example, the yarn could be passed over two small rotating members disposed at an angle of about 45° with respect to the direction of yarn travel in the heating device. With this arrangement, it is possible to guide yarn in a helical path successively over the two members in such a manner that the resistance to yarn rotation, or twist, would be reduced to zero. Moreover, a flexible tube may be bent through an angle of 180° and then driven about its axis at a speed of revolutions corresponding to the turns per inch imparted by the false twist device. Operation of this embodiment could correspond generally to that of known fatigue testers such as shown in U.S. Patent No. 2,657,573, with the flexible tubing appearing at element 5.

It is pointed out that, in some instances, it may be desired to cool yarn 11 immediately after heating and twist setting. This unit could be similar to heater 16, but of course would be provided with a cooling medium. These heaters and/or cooling devices may be of various forms. It is possible to construct the same as a flat member, to curve them either longitudinally or transversely, and they may be shaped in the form of a trough or a tube, as shown.

It should also be pointed out that this invention is useful in any type of twist setting operation, whether the twist be false, as illustrated, or positive.

Inasmuch as other modifications will become apparent to those skilled in this art, it is intended that this invention be limited only to the scope set forth in the following claims.

What is claimed is:

1. A yarn texturizing apparatus comprising a twist device, a twist-set device, means for guiding yarn at least twice through said twist-set device before passage into said twist device, and means for vibrating said guide means to produce slippage between the same and the yarn to reduce the friction therebetween and thereby permit back up of yarn twist over said guide means.

2. Apparatus as set forth in claim 1 wherein said last named means vibrates said guide means in an axial direction thereof.

3. Apparatus as set forth in claim 1 wherein said last named means vibrates said guide means in a radial direction thereof.
  4. Apparatus as set forth in claim 1 wherein said last named means vibrates said guide means both in an axial and in a radial direction thereof.
  5. Texturizing apparatus comprising a false twist device for imparting twist to yarn passing therethrough, a heater for setting said twist, means for feeding yarn into said heater and false twist device, a twist barrier for preventing back up of twist into said feeding means, means for guiding said yarn at least twice through said heater before passage into said false twist device, means for vibrating said guide means to produce slippage between the same and the yarn to reduce the friction therebetween and thereby permit back up of twist thereover, and means for withdrawing twist-set yarn from said false twist device.
  6. Apparatus as set forth in claim 5 wherein said withdrawing means also imparts a positive twist to said yarn.
  7. In a method of texturizing yarn including the steps of twisting yarn and passing the twisted yarn through a fixation zone to set the twist therein, the improvement comprising the steps of guiding said yarn back and forth at least twice through said fixation zone, and vibrating the yarn at each reversal point in order to produce slippage between the same and the yarn to reduce the friction therebetween and thereby prevent twist stop.
